UNITED STATES PATENT OFFICE.

ALEXANDER D. GRANT, OF SAN JOSE, CALIFORNIA.

SANITARY TOILET-BOWL.

1,178,852.

Specification of Letters Patent. Patented Apr. 11, 1916.

Application filed August 9, 1915. Serial No. 44,411.

To all whom it may concern:

Be it known that I, ALEXANDER D. GRANT, a citizen of the United States, residing at San Jose, in the county of Santa Clara and State of California, have invented new and useful Improvements in Sanitary Toilet-Bowls, of which the following is a specification.

This invention relates to a sanitary toilet bowl.

The object of the present invention is to provide a receptacle in or exterior of a toilet bowl adapted to receive a disinfectant and to provide means for automatically discharging a quantity of same when the bowl is flushed.

The invention consists of the parts and the construction and combination of parts as hereinafter more fully described and claimed having reference to the accompanying drawings, in which—

Figure 1 is a central, vertical section of the toilet bowl. Fig. 2 is a plan view on line 2—2, Fig. 1.

Referring to the drawings in detail, A indicates in general the toilet bowl, 2 an intake opening which is connected with a tank or other source of water supply, not here shown; and 3 a discharge opening which is connected with a main chamber 4 by means of a passage, indicated at 5. Formed in the intake opening 2 just above the opening 6 leading into the main chamber, is a pocket or receptacle 7, which is perforated around the sides and the bottom, as indicated at 8 and 9; and formed just above said pocket, is an opening 10, which is adapted to be closed by means of a removable cover 11. The pocket 7 is adapted to receive or form a container for a disinfectant, said disinfectant preferably being in the form of a solid, which is slowly dissolved by the action of the water.

Formed in the intake opening 2 just below the disinfectant receiving chamber 7, is a barrier 12 and similarly formed near opening 6, is a barrier 13; and extending from a point just rearwardly of barrier 13 to the lower portion of the bowl, indicated at 14, is an auxiliary drain passage 15, the function of which will later be described. The removable cover 11 provided in this instance consists of the cover 11, on the lower end of which is formed a threaded extension 16, which screws into a cross-bar 17;

this cross-bar is sufficiently long to extend across the opening 10 and is lowered into its normal position through slots 18, formed in the side of opening 10. The cover 11 and bar 17 is then slightly turned until the bar 60 assumes the position approximately such as shown in Fig. 2, out of alinement with slots 18. The cover section is then turned by means of a spanner wrench inserted into depressions 19 formed in the cover, thus 65 drawing the cross-bar up against the under side of the opening 10; and thoroughly securing the cover in position.

In operation it will be seen that flushing of the toilet will cause the water from the 70 source of supply to enter opening 2 in the direction of arrow *a*. A portion of the water is here deflected upwardly, as indicated by arrow *b*, and is in this manner forced through openings 8 into the chamber 7 containing the solid, but soluble disinfectant. The water then passes through opening 6 in the direction of the arrow, through the main chamber 4; passage 5, and finally through the discharge opening 3; in the usual manner. The toilet bowl is in this manner flushed and the contents of chamber 7 become so saturated with water that a quantity of same is dissolved. The dissolving matter will then drain through the bottom perforations 9 and collect between barriers 12 and 13, where it is finally permitted to drain through passage 15 into the lower portion of the bowl, thus thoroughly disinfecting 90 the bowl and the water contained therein.

In practice it has been found that certain varieties of disinfectants have a tendency to stain the bowl. This is obviated in the present instance, as none of the disinfectant is admitted through the main opening 6 and the bowl. The auxiliary drain passage 15 being provided for the purpose of admitting the disinfectant to the lower portion of the bowl, where it is furthermore 100 most efficiently applied.

The materials and finish together with the construction and the location of the device, may otherwise be such as the judgment and experience of the manufacturer may dictate.

I wish it understood that various changes in form, proportions and minor details of construction may be resorted to within the scope of the appended claims, and that I do not wish to limit myself to the specific 105 design and construction here shown.

Having thus described my invention, what I claim and desire to secure by Letters Patent is—

1. In a toilet, a bowl having a water inlet at the upper rear edge, a container for a solid soluble disinfectant located above said inlet, and having openings in the bottom, a chamber formed below the inlet and the container to receive the solution, and a passage formed in the bowl and leading from said chamber to the bottom of the bowl.
2. The combination with the water inlet opening of a toilet bowl, of a perforated container formed in said inlet opening, said container adapted to serve as a receptacle for a disinfectant which is in a solid, but soluble state, and a barrier member mounted in the inlet opening below the disinfectant container to direct a portion of the flushing water through the container when the toilet is flushed.

3. The combination with the water inlet opening of a toilet bowl, of a perforated container formed in said inlet opening, said container adapted to serve as a receptacle for a disinfectant which is in a solid, but soluble state, a barrier member mounted in the inlet opening below the disinfectant container, a second barrier member mounted forward of the first-named barrier member to form a pocket below the disinfectant container, and a drain passage formed in the bowl connecting said pocket with the lower portion of the main chamber in the bowl.

In testimony whereof I have hereunto set my hand in the presence of two subscribing witnesses.

ALEXANDER D. GRANT.
